UNITED STATES PATENT OFFICE.

ANDREW B. YETTER, OF NEW YORK, N. Y.

MOVING-VAN.

SPECIFICATION forming part of Letters Patent No. 740,350, dated September 29, 1903.

Application filed February 25, 1903. Serial No. 144,959. (No model.)

To all whom it may concern:

Be it known that I, ANDREW B. YETTER, a citizen of the United States, and a resident of the city of New York, borough of Manhattan, in the county and State of New York, have invented a new and Improved Storage Van-Box and Carrier, of which the following is a full, clear, and exact description.

The purpose of the invention is to provide a construction of moving-van in which the box or body is roller-supported upon the running-gear and means for providing for retaining the van or box upon the running-gear while in transportation, for example, from the storage-house to the house or apartment from which the material is to be removed and to so construct the truck or running-gear that after the body or box has received its load and is securely sealed the said box or body may be quickly and conveniently released from its fastening devices upon reaching the storage-house and expeditiously and without impediment transferred to a platform-truck, so that the sealed receptacle can be readily carried to any desired position in said storage-house by the assistance of an elevator or by other usual means and upon being removed from the platform-truck can be set up in its locked and sealed condition, thus assuring, as far as possible, the storage-receptacle being stored in the same locked condition as that in which it left the premises at which the load was received. Under such a construction of moving-van it is evident that when a van of the character described is loaded and the key is delivered to the owner of the contents of the van the contents of the van may be inspected at any time and under ordinary circumstances with the assurance at the first inspection that the contents of the storage box or body of the van are in the same position and in the same quantity as when loaded. Under such a construction of storage-van it is evident that separate compartments in storage-houses need not be constructed, and as each box or body constitutes a safe or receptacle in itself its contents are practically secure. It is further evident that such a construction of van-box dispenses with numerous handlings of the material to be transported, thus economizing in time as well as wear and tear of the articles.

Another purpose of the invention is to so construct the truck that the forward hounds, having the driver's seat, front wheels, and draft device attached, may be quickly removed from the main portion of the truck carrying the body or box, means being provided at such time for sustaining the forward end of the main portion of the truck, thereby enabling one team after placing a storage-van in position to receive a load to be utilized to draw another van into position for loading and then return and be connected with the van-box and its wheeled support precedingly positioned.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a longitudinal vertical section through the improved construction of storage van-box and support, the section being taken practically on the line 1 1 of Fig. 2. Fig. 2 is a plan view of the complete truck employed to support a carrier or van box or body. Fig. 3 is a rear elevation of the vehicle complete. Fig. 4 is a plan view of a platform-truck employed for removing the van box or body from the running-gear of the vehicle to a storage position within the storage-warehouse. Fig. 5 is a section taken practically on the line 5 5 of Fig. 4, illustrating more in detail the construction of the platform-truck; and Fig. 6 is an enlarged view illustrating a partial vertical section through the storage van-box or body and its roller-support on the running-gear of the vehicle.

A represents a box or body, which is adapted to be carried by a wheel-supported frame or running-gear B and is removable from such frame. This box or body A may be constructed in any suitable or approved manner and may be of any desired dimensions, but is usually made as near as possible waterproof and fireproof without adding materially to its weight.

The box or body A is preferably permanently closed at its sides, top, bottom, and front and is provided with one or more (pref-

erably two) doors at its rear or side having suitable hinged connection with the body proper. These doors when two are employed, as illustrated in Fig. 3, have one a 5 transverse bar 11, attached thereto exteriorly, transversely, and rigidly at about its center, while the opposing door has a corresponding bar 12, pivotally attached to the door and movable upward and downward from a keeper 10 13, secured to the door upon which the fixed bar is located. Both of these bars 11 and 12 at their opposing ends have apertured flanges through which the bail of a padlock, for example, may be passed in order to lock the 15 doors 10 closed, as is also fully shown in Fig. 3. The box or body A is further provided with angular channel-tracks 14, securely fastened to its bottom portion and extending longitudinally thereof, one at each side of 20 the center, as is shown in Figs. 1, 3, and 6. The box or body A is adapted to rest upon and to be carried by the running-gear B, which is preferably of the character shown particularly in Fig. 2. This running-gear 25 consists of a rear or main section b and a forward and auxiliary section b', detachably connected with the rear or main section b. The rear or main section b is usually of rectangular form and comprises parallel side 30 beams 15, a front cross-bar 16, and a rear cross-bar 17, the said bars being connected in any approved manner suitable to the requirements of the box or body A to be supported.

35 An axle 18 is located at the rear portion of the main section b of the running-gear, extending beyond its sides, and at the ends of this axle 18 suitable wheels 19 are mounted to revolve. Friction-rollers 20 are journaled 40 in suitable supports 21 at suitable intervals apart longitudinally at the upper faces of the side beams 15, as is shown particularly in Figs. 2 and 6. Rear hounds 22 are attached to the rear portion of the main section b of the running-gear B, and these hounds extend 45 forwardly beyond the front cross-bar 16, converging as they extend forward. The said rear hounds 22 are connected at their forward ends and are apertured to receive a 50 king-bolt 23. This king-bolt 23, as is best shown in Fig. 1, passes down in the usual manner through a forward axle 24, constituting a portion of the auxiliary or front section of the said running-gear B. The construction 55 of this front or auxiliary section b' of the running-gear B consists, in addition to the front axle 24, of forward hounds 26, which are suitably attached to the forward axle and extend forwardly and rearwardly beyond the 60 same, the forward hounds at their rear ends being connected by a cross-bar 27, having friction-rollers, if desired, and in the normal position of the two sections of the running-gear B the rear cross-bar 27 of the forward 65 hounds 26 is below the forward cross-bar 16 of the rear or main section b of the said running-gear. The forward ends of the for-

ward hounds are connected by a suitable cross-bar 28, upon which a proper draft device 29 is pivotally mounted, and on the forward axle 24 suitable supporting-wheels 25 are mounted to turn. The driver's seat 30 forms also a portion of the front or auxiliary section b' of the running-gear B. This driver's seat 30 is supported by standards 31 and 70 braces 32, if necessary, the said standards being connected in any suitable or approved manner with the forward axle 24, as is best shown in Fig. 1. In connection with the driver's seat 30 a foot-rest 33 is employed, 75 also supported by the standards 31 and having an opening therein which permits ready access to the king-bolt 23, as is shown in both Figs. 1 and 2.

When the van is in position for loading, it 80 is frequently desirable that the forward section b' of the running-gear shall be detached from the rear or main section b, which is accomplished by the removal of the king-bolt 23, in order that the forward section b' of the 85 running-gear may be drawn off and utilized for connection with another rear or main section b, so as to bring another box or body A in position to receive a load. At such time the main or rear portion b of the running-gear B should have a support at its forward 90 portion, and such a support is provided by pivoting a shaft 35 below the frame of the rear or main section b, adjacent to the front cross-bar, as is shown also in Figs. 1 and 2, 95 and providing this shaft 35 with legs 34, which may be dropped down to an engagement with the ground, as is shown in Fig. 1. When these supporting-legs 34 are not needed, they 100 are carried upward and rearward, as is illustrated in dotted lines in Fig. 1, and are held in their upper position by suitable latches 36.

The box or body A is held from accidentally slipping from off its wheeled support by stake-blocks 37, which are passed down 105 through suitable openings 39, made in the rear cross-bar 17 of the main section b of the running-gear, and the said body or box A is prevented from accidentally moving too far forward by similar stake-blocks 38, which 110 may be passed down through openings 40 in the forward cross-bar 16 of the said main section b of the running-gear or through openings 41, located in the forward portion of the 115 rear hounds 22, or through any other convenient part of the forward portion of the 120 running-gear.

It is obvious that when a box-body has been loaded and sealed and has been carried to the storage warehouse it can be readily and 125 bodily separated from the running-gear by simply removing the rear stake-blocks 37, as the roller-supports for the said box or body A enable the said box or body to be readily handled upon the said running-gear, either 130 to place it in position thereon or to remove it bodily therefrom, as stated.

In Fig. 1 I have illustrated the van in position to receive a load, the rear wheels of the

truck being backed against the curb 42 of the sidewalk, and in order that the material or the articles to be loaded into the box or body A shall be protected from the inclemency of the weather I preferably use a canopy 43, extending from the rear of the said box or body A to the passage-way through which said material to be loaded is to be taken.

When the van reaches the storage-warehouse, a platform-truck C is employed to receive the box or body A when it is removed from the running-gear, and preferably this platform-truck is constructed as is shown in Figs. 4 and 5 and may be of any desired shape or dimensions. As illustrated, however, the truck consists of a rectangular frame having a central cross-bar, and upon the upper face of the side bars of the said truck friction-rollers 44 are located, which enable the body or box A to be readily handled on the truck and to be conveniently removed therefrom when the body or box is to be placed in position for storage. This truck C is provided with a central caster-wheel 45, 25 extending downwardly from the central cross-bar of the frame or body of the truck, and with corner caster-wheels 46, extending in the same direction; but the corner caster-wheels 46 do not extend down as far as the central 30 caster-wheel 45, so that the truck can be readily supported when it is traveling by means of the corner caster-wheels at one end and the central caster-wheel and so that when the truck is to be turned it need simply 35 be brought to a horizontal position, whereupon it may be pivotally supported on the aforesaid central caster-wheel 45.

Having thus described my invention, I claim as new and desire to secure by Letters 40 Patent—

1. A moving-van or similar vehicle, constructed of a running-gear, and a body removably mounted thereon, said running-gear comprising a rearward wheel-supported section and a forward wheel-supported section, combined with hounds extending from said

rearward section to the axle of the forward section and having detachable connection therewith, and additional hounds extending rearwardly of said axle, to and beneath the 50 forward part of said rearward section.

2. A moving-van or similar vehicle, constructed of a running-gear, a body removably mounted thereon, means for preventing endwise movement of the body, said running-gear comprising a rearward wheel-supported section and a forward wheel-supported section, combined with hounds extending from said rearward section, and having pivotal and detachable connection therewith, and additional hounds extending rearwardly of said 55 axle, to and beneath the forward part of said rearward section.

3. A moving-van or similar vehicle, constructed of a running-gear, a body removably mounted thereon, said running-gear comprising a rearward wheel-supported section and a forward wheel-supported section, the section first named being provided with adjustable supports, intermediate the ends 70 thereof, combined with hounds extending from said rearward section to the axle of the forward section, and having detachable connection therewith, and additional hounds extending rearwardly of said axle, to and beneath the forward part of said rearward section. 75

4. In storage-vans, a running-gear consisting of a rear wheel-supported section, a forward wheel-supported section, pivotally and 80 removably connected with the rear section, and adjustable supports carried by the rear section at a point intermediate of its ends, for the purpose described.

In testimony whereof I have signed my 85 name to this specification in the presence of two subscribing witnesses.

ANDREW B. YETTER.
